UNITED STATES PATENT OFFICE.

CLARENCE H. HAPGOOD, OF TOLEDO, OHIO.

SAFETY RAZOR.

REISSUED

Application filed May 2, 1925. Serial No. 27,357.

This invention relates to safety razors and has for its principal object the provision of a relatively permanent blade of high grade steel in a frame adapted to act 5 as a handle during the shaving operation and a guide during the operations of stropping and honing.

It has long been customary to consider safety razor blades as small, thin strips of 10 medium grade steel intended for use only a comparatively few times after which they are discarded. It is an object of this invention to replace the usual flimsy temporary blades with a relatively heavy blade of 15 high grade razor steel which will last practically as long as the frame and other parts of the device. Such blade is pivotally mounted within a frame and means are provided to position it at any desired angle 20 relatively to the frame.

Another object of the invention is the provision of a holder adapted to detachably engage both the blade and frame, and which can be adjustably secured to the frame in 25 several positions.

A further object of the invention is the arrangement of means for bending the portion of the holder member adjacent the edge of the blade to bring such portion to any 30 desired position relatively to the edge of the blade.

A further object of the invention is the arrangement of means for holding the blade during the stropping and honing operations 35 whereby the blade may be slid in the usual manner over the surface of ordinary strops and hones.

Other objects and advantages will be apparent from the following description, 40 wherein reference is made to the accompanying drawings illustrating a preferred embodiment of my invention and wherein similar reference numerals designate similar parts throughout the several views.

45 In the drawings:

Fig. 1 is a plan view of my improved safety razor with the detachable holder removed.

Fig. 2 is a side view of the razor in the 50 positions assumed while being stropped.

Fig. 3 is a detail perspective view of the auxiliary holder for engaging the blade during the stropping operation.

Fig. 4 is a similar view of the blade and 55 holder frame in position to co-act with the auxiliary holder.

Fig. 5 is a detail side view of the razor blade.

Fig. 6 is an end view of my improved 60 razor in position for shaving.

Fig. 7 is a bottom plan view thereof.

Fig. 8 is a side elevation thereof.

Fig. 9 is a detail elevation of the detachable holder for positioning the blade at any desired angle relatively to the holder, frame 65 and

Fig. 10 is a detail section taken substantially on the line 10—10 of Fig. 7.

Referring now to the drawings, the numeral 5 designates a handle and 6 a holder 70 frame detachably secured thereto, as by a threaded stem 7. The holder frame 6 is substantially U-shaped and provided with threaded apertures in its extremities for the reception of the fulcrum screws 8, which are 75 preferably formed substantially as shown in Fig. 10 with round tenons 8^a adapted to fit within the apertures 9^a in the blade 9 to permit ready rotation of the blade to position it at any desired angle relatively to the holder frame 6. The blade 9 is preferably an integral piece of high grade steel having a relatively thick rear portion in which are located the apertures 9^a and a body portion tapering gradually to the edge portion 85 which is preferably beveled substantially as shown. If desired the body portion of the razor 9 may be hollow ground between the beveled edge portion and the thickened rear portion, whereby only the beveled edge portion 90 and the sides of the thickened rear portion contact a strop 10 during the stropping operation, or a hone during a honing operation (note Fig. 2). The blade can be honed and stropped without being removed from 95 the razor frame, and on the usual hones and strops now in general use. The blade has a large wearing surface against the hone or strop and can always be kept to a super-keen edge, after the manner of the old-fashioned razors rather than the modern safety razors of ribbon steel. The honing or stropping operation with my improved safety razor is performed exactly like the honing or stropping of an old-fashioned 100 razor except that the blade itself is grasped by the operator through the medium of an auxiliary holder 11 (note Fig. 3), and then slid along the surface of the strop or hone as long as desired. The auxiliary holder 11 105 is formed with a pair of clamping tines 12 adapted to engage the body portion of the

razor intermediate the beveled edge portion and the thickened rear portion of the blade. In the illustrated embodiment I have provided a pair of notches 13 in the body portion of the razor blade adjacent one side thereof for the reception of the tines 12 of the auxiliary holder. This insures the grasping of the blade by the auxiliary holder at the right location. The notches 13 are 10 preferably of such depth that the outer surfaces of the tines 12 will not extend beyond the opposite faces of the razor blade and contact the strop or hone instead of permitting the desired contacts only between 15 the beveled edge portion of the blade and its thickened rear portion. During the honing or stropping operation the razor frame 6 depends from the thickened rear portion of the blade 9 and acts as a pendulum to 20 maintain the blade in contact with the strop or hone. Moreover, the arms of the razor frame 6 act as guides for preventing the lateral slipping of the blade during the honing or stropping operations. Preferably the 25 strop or hone used is of slightly less width than the distance between the arms of the U-shaped frame 6 to permit a slight turning of the frame so that the blade will set with its edge at an angle to the sides of the strop 30 other than a right angle. This permits the usual positioning of the blade relatively to the surface of the strop or hone, and the arms of the frame then engage the sides of the strop to prevent deviation from the 35 desired angle while the blade is being slid along the surface of the strop or hone.

The operation of honing or stropping would, accordingly, be carried out by merely inserting the strop or hone between the 40 arms of the razor frame 6 and holding it in substantially horizontal position. The handle 5 and frame 6 then hang from the thickened surface of the blade 9 and the blade rests upon the upper surface of the strop 45 substantially as shown in Fig. 2. The auxiliary holder 11 is then inserted into the notches 13 of the blade and the blade with its attached frame and handle alternately pushed and pulled over the surface of the strop or hone by pressure on the holder 11. At the end of each stroke the blade is turned 50 by partially rotating the holder 11 so that the beveled edge portion of the blade is pointed in the desired direction, and this position is then maintained during the remainder of the stroke. These alternate 55 strokes over the strop or hone may be continued as long as desired.

The blade may now be used for shaving, 60 without detaching it from the razor frame 6, but after the auxiliary holder 11 has been removed. A guard member 14, preferably formed substantially as shown in Fig. 9, is positioned upon the blade 9 and the inner 65 face of the razor frame 6. The guard mem-

ber 14 herein shown comprises a guard plate having rounded and downturned teeth 15 adjacent one end and a securing member 16 of resilient material secured upon its opposite extremity, whereby the guard plate is 70 secured upon the razor blade, the securing member 16 being adapted to snap into position over the thickened portion of the blade 9 and press against the inner face of the holder frame 6. The guard member and securing member 16 are preferably welded or otherwise suitably united so as to form a substantially integral piece. The angle at which the blade 9 is held relatively to the handle 5 may be adjusted to suit the convenience of the user by virtue of a plurality of aligned apertures 17 in the securing member 16. As herein shown enlarged central apertures are adapted to fit over the threaded stem 7 of the handle 5 and smaller side apertures are adapted to fit over studs 18 extending from the inner surface of the razor frame 6, substantially as shown in Fig. 7. The endmost guard teeth 15 are preferably 85 bent upwardly and over the sides of the blade to serve in positioning the blade upon the guard member and prevent the accidental relative movement of the blade and guard member during the shaving operation. The free extremity of the securing member 90 16 is preferably curved to provide a finger engaging projection 16^a to facilitate the positioning of the guard member within the razor frame and its removal therefrom.

If desired, provision may be made for 100 slightly moving the central teeth 15 of the guard plate toward or away from the edge of the blade 9. As herein shown the endmost guard teeth 15 are provided with downturned apertured ears 19 for the reception 105 of the stub shafts 20 eccentrically mounted in the ends of the adjusting roller 21. This roller is substantially cylindrical, but with the stub shafts eccentrically mounted in its ends and journaled in the ears 19 of the endmost guard teeth, the rotation of the roller 110 will serve to bend the central teeth 15 of the guard plate toward the blade 9 as the thicker portion of the roller comes between the shafts 20 and the teeth. Then as the wider portion 115 of the roller moves in the opposite direction the resiliency of the metal of the plate 14 will serve to move the central teeth away from the blade 19, the under surface of the teeth remaining always in engagement 120 with the periphery of the roller 21. A knurled handle 22 may be provided for ready rotation of the adjusting roller 21. It will be noted that the adjusting roller is 125 carried by the guard member 14 and is removed with the guard member when it is desired to strop or hone the blade. After the desired adjustment of the blade relatively to the central guard teeth 15 is once secured, it may be held indefinitely, the central guard 130

teeth remaining in the desired position under the control of the adjusting roller 21 regardless of whether the guard member 14 is secured upon the razor blade.

5 It will be noted that the blade 9 and associated parts can be readily cleaned after the shaving operation, or whenever desired. When the guard member 14 is removed from the blade and razor frame, the blade and frame can be thoroughly scoured by holding under the faucet and allowing the running water to remove the extraneous matter, or the frame and blade may be swished in water standing in a bowl or the like, the operator 10 holding to the tip of the handle 5. Likewise the guard member 14 may be readily cleansed by immersion in a standing body of water or held in the stream from a faucet.

Moreover, it will be noted that my improved safety razor is particularly designed for speedy action. The guard member 14 can be snapped on the blade, and instantly removed by grasping the projection 16^a. The 15 blade is readily stropped with a few strokes over the surface of the strop, and the cleansing operation can be quickly completed. The frame 6 can then be disassembled from the handle 5 and the entire mechanism housed in any desired container. The edge portion 20 of the blade 9 is preferably folded into the U-shaped frame 6 when the device is housed in a container.

While it will be apparent that the illustrated embodiment of my invention herein disclosed is well calculated to adequately fulfill the objects and advantages primarily stated, it is to be understood that the invention is susceptible to variation, modification and change within the spirit and scope of 25 the subjoined claims.

Having described my invention, I claim—

1. In a safety razor, a razor frame, a handle adapted to be secured thereto, a pair of tenons secured in the frame, and a blade pivotally mounted on the tenons, the blade being notched to receive a stropping tool.

2. In a safety razor, a razor frame, a handle adapted to be secured thereto, a blade directly secured within the frame and having an edge portion and a relatively thick rear portion, and a guard plate arranged to engage the frame, the sides of the edge portion of the blade and the central portion of the rear portion of the blade.

3. In a safety razor, a razor frame, a handle adapted to be secured thereto, a blade directly secured within the frame and having an edge portion and a relatively thick rear portion, a guard plate arranged to engage the sides of the edge portion and the central portion of the rear portion of the blade, and means for securing the guard plate upon the frame in a plurality of adjusted positions.

4. In a safety razor, a razor frame, a han-

dle adapted to be secured thereto, a blade directly secured within the frame and having an edge portion and a relatively thick rear portion, a guard plate arranged to engage the sides of the edge portion and the central portion of the rear portion of the blade, means for securing the guard plate upon the frame in a plurality of adjusted positions comprising spaced projections on the frame, and a flexible frame engaging portion of the guard plate having a plurality of aligned apertures therein adapted to contact with the projections on the frame.

5. In a safety razor, a razor frame, a handle adapted to be secured thereto, a blade directly secured to the frame, means for securing the blade in predetermined angular relation to the frame comprising a toothed guard plate adapted to engage the blade and frame, and means carried by the guard plate for moving the teeth thereof to adjust the distance of the teeth from the edge of the blade.

6. In a safety razor, a razor frame, a handle adapted to be secured thereto, a blade directly secured to the frame, and means for securing the blade in predetermined angular relation to the frame comprising a toothed guard plate adapted to engage the blade and frame comprising an eccentric roller mounted upon the guard plate and engaging the teeth.

7. In a safety razor, a razor frame, a handle adapted to be secured thereto, a blade directly secured to the frame, and a detachable holder adapted to directly engage the blade for moving the blade over a strop.

8. In a safety razor, a razor frame, a handle adapted to be secured thereto, a blade directly secured to the frame, and a second handle having spaced jaws adapted to engage the blade for moving the blade over a strop.

9. In a safety razor, a razor frame, a handle adapted to be secured thereto, a blade directly secured to the frame, and having a notch adjacent one side edge, and a second handle adapted to fit in said notch of the blade for moving the blade over a strop.

10. In a safety razor, a razor frame, a handle adapted to be secured thereto, a blade directly secured to the frame and having a pair of aligned notches adjacent one side edge, and a second handle having a pair of spaced jaws adapted to fit into said notches of the blade for moving the blade over a strop.

11. In a safety razor, a razor frame, a blade pivoted upon the frame and having a notch adjacent one side edge, and a detachable holder adapted to fit in said notch of the blade for moving the blade over a strop.

In witness whereof I hereunto set my hand.

CLARENCE H. HAPGOOD.
